UNITED STATES PATENT OFFICE.

WILLIAM NOTTER, OF CHICAGO, ILLINOIS.

IMPROVEMENT IN PORK-PACKERS' TABLES.

Specification forming part of Letters Patent No. **155,201**, dated September 22, 1874; application filed March 9, 1874.

To all whom it may concern:

Be it known that I, WILLIAM NOTTER, of Chicago, in the county of Cook and State of Illinois, have invented a new, useful, and Improved Hog-Bench or Table for Pork-Packers, of which the following is a full, clear, and exact description, which will enable others skilled in the art to which my invention appertains to make and use the same, reference being had to the accompanying drawing forming a part hereof, and in which—

Figure 1 is a top or plan view of my improved table; Fig. 2, a like view of the same when the wings are removed; and Fig. 3, a cross-section in the plane of the line *xx*.

Like letters of reference indicate like parts. In preparing hogs for the purpose of producing packed pork a long narrow table is usually employed, on each side of which the workmen are arranged. The hogs are caught and bled and then scalded and delivered upon one end of the table. The bristles are then removed by one or more men standing at each side of the table, near that end on which the hogs are delivered. The hogs are then turned over on the table, and thus passed to other workmen who employ scrapers for the purpose of removing the hair. The hogs are then rolled from the scrapers to the shavers, and the latter, after performing their work, deliver the shaved hogs to the header and gammer. The header and gammer performs his work and then swings the hogs from the table. The men whose work it is to deliver the hogs upon the table can generally deliver them faster than the men along the table can perform their part of the work. If the number of men along the table is considerably increased, these men, when too many are employed, are liable to be in the way of each other, and their work is thus impeded. In other words, only a restricted amount of work can be done with advantage on the same table at the same time.

The object of my invention is to make a ta-

ble at which either one or two gangs of men may be employed with advantage; and to that end it consists of a table having a removable center and removable or folding lateral extensions, substantially as hereinafter described and set forth.

In the drawing, A represents the central part of the table. B is the removable center, and C C are the removable lateral extensions. *aa* are the legs. When the center is removed and the extensions applied, as represented in Fig. 1, two gangs of men may be employed, one gang standing in the central opening and the other standing around the outer edge of the table, each gang facing the other. The hogs are delivered on the end *e*, the first hog being passed along one of the lateral extensions to the other end, and the next hog along the other extension, and so on alternately.

When the workmen are arranged in this manner a comparatively short table may be employed, and the workmen are not likely to impede each other in their work.

When the center is retained and the lateral extensions are removed, a long narrow table is formed, such as is commonly used for the purpose set forth.

Either one or two gangs of men may be employed on the form of table represented in Fig. 1.

The extensions C C may be hinged so as to be folded out of the way.

Having thus described my invention, what I claim as new, and desire to secure by Letters Patent, is—

A hog-bench having the removable center B and the lateral extensions C C, substantially as shown and described, for the purposes set forth.

WILLIAM NOTTER.
